UNITED STATES PATENT OFFICE.

WLADISLAUS RAKOWSKI, OF DAVIS, WEST VIRGINIA.

NON-REFILLABLE BOTTLE.

1,077,915.

Specification of Letters Patent.

Patented Nov. 4, 1913.

Application filed August 6, 1912. Serial No. 713,628.

To all whom it may concern:

Be it known that I, WLADISLAUS RAKOWSKI, subject of the Emperor of Germany, residing at Davis, in the county of 5 Tucker and State of West Virginia, (whose post-office address is Palmerton, Carbon county, Pennsylvania,) have invented certain new and useful Improvements in Non-Refillable Bottles, of which the following is 10 a specification.

This invention relates to non-refillable bottles and has as its object to provide an extremely simple, though highly efficient valve and valve-guard for such a bottle.

15 It is one aim of the invention to provide a valve for a non-refillable bottle, which valve, when in closed position, will effectually seal the neck of the bottle, whereby to prevent the introduction of liquid into the bottle, 20 although when the bottle is tilted to discharge its contents, the valve will open so fully as to in no way obstruct the flow of liquid from the bottle.

For a full understanding of the invention 25 reference is to be had to the following description and accompanying drawing, in which:—

Figure 1 is a vertical sectional view 30 through the device embodying the present invention, the same being arranged with a bottle neck. Fig. 2 is a top plan view illustrating a slightly modified form of the guard. Fig. 3 is a view in side elevation of the guard illustrating a further modification of the guard. Fig. 4 is a vertical sectional view illustrating a modified form of the valve, parts being shown in elevation. Fig. 5 is a plan view of the structure shown 35 in Fig. 4 applied within the bung-hole of a barrel. Fig. 6 is a detail perspective view 40 of the valve and its support detached from its casing. Fig. 7 is a plan view illustrating a modified form of valve.

Corresponding and like parts are referred 45 to in the following description and indicated in all the views of the accompanying drawing by the same reference characters.

In the form of the invention shown in 50 Figs. 1, 2, 3 and 6 of the drawing, the valve casing is indicated by the numeral 1 and is preferably cylindrical in form and of hard rubber, although it may be of any other suitable material, if desired. At its upper end the casing 1 is formed with an 55 integral inwardly extending annular flange 2. The guard for the valve in the form of

the invention shown in Fig. 1 of the drawing, is in the nature of a wire screen 3 of circular form and preferably of fine mesh which is disposed against the flange 2 and 60 is held in place within the upper end of the casing 1 by means of a ring 4 which may be resilient and sprung into place or may be secured in place in any other desired manner.

At a point between its upper and lower 65 ends the inner surface of the casing 1 is formed with an annular groove 5 and within this groove is seated a soft rubber packing ring or gasket 6 which serves as a seat for the valve, as will be presently specifically pointed out. The support for the valve 70 is formed from a single length of wire which is bent to form an intermediate or connecting portion 7 which is straight and of a length to extend entirely across the 75 interior of the casing 1. The wire at the ends of the portion 7 is bent downwardly and inwardly at an acute angle as at 8 and thence outwardly at an acute angle as at 9, the portions 9 being parallel to the intermediate portion 7. The wall of the valve 80 casing 1 is formed at diametrically opposite points with openings 10 which are arranged to register with sockets 11 formed in the inner surface of the bottle neck which is 85 indicated by the numeral 12. The portions 9 of the valve support are slidably fitted through the openings 10 and, when the casing 1 is inserted into the bottle neck, and the openings 10 are brought into registration with the sockets 11, the portions 9 are sprung by the resiliency of the wire 90 from which they are formed, into the said sockets 11, thereby securely locking the valve casing in place within the bottle 95 neck.

It will be observed from inspection of Fig. 1 of the drawing that the engagement of the portion 9 of the valve support in the opening 10 in the wall of the valve casing 100 serves to support the member within the said casing beneath the guard screen 3. The valve proper consists of two leaves 13 which are formed with interfitting pintle lugs 14 arranged to fit snugly so as to prevent the entrance of liquid between the leaves. In assembling the valve leaves 13 with the wire supporting member above described, the intermediate portion 7 of the said member is inserted through the registering pintle lugs 14, in the manner clearly 110 shown in Fig. 6 of the drawings.

It will be observed that the portion 7 of the supporting member is located in substantially the same plane as the packing ring 6 which constitutes a seat for the valve leaves 13, it being understood that the arcuate edge portions of these leaves rest upon the said seat 6 when the valve is in closed position and the bottle is upright.

In the form of the invention shown in Figs. 4 and 5 of the drawing, the valve casing is indicated by the numeral 15 and is preferably formed of metal, although it may be of any other material, and the said casing is formed at its upper end with an inwardly projecting flange 16 and at its lower end with a flange 17.

A wire screen 18 is disposed against the under side of the flange 16, and a ring 19 corresponding to the ring 4 is arranged within the casing to hold the screen in place. In this form of the invention a flat-sided packing ring 20 is disposed upon the lower flange 17 of the casing in the manner illustrated in Fig. 4 and the valve-leaves which are here indicated at 21, are supported upon a hinged pin 22 which is straight and extends diametrically across the casing and engages at its ends in the wall thereof. In this form of the invention a rubber ring 23 is fitted upon the outer surface of the casing 15 and serves to retain the casing in place within the neck of a bottle or the bung-hole of a barrel into which the casing is inserted. While this form of the invention has been here shown as applied within the bung-hole of a barrel, it will be understood that it may equally as well be employed within the neck of a bottle.

In the form of the invention shown in Fig. 2 of the drawing, the guard is in the nature of a metallic disk 24 formed with a number of small openings 25, it being understood that this disk is arranged to take the place of the screen 3, previously referred to.

In that form of the invention shown in Fig. 3 of the drawing, the valve casing is formed with a tongue-like upper end 26 having a number of relatively extending slits 27 which permit of the out-flow of liquid from the bottle.

In place of the two leaf valves shown in Fig. 6, a valve similar to that shown in Fig. 7 may be employed. This valve includes a single circular leaf or body member 28 mounted upon a small hinge 29, the ends of the pintle pin 30 of which seat in the walls of the casing. This valve may be employed with any of the bottle closers shown, and will be found equally effective with all.

Having thus described the invention what is claimed as new is:—

1. In a non-refillable bottle, a valve casing, a valve-seat within the casing, a valve support arranged within the casing and including a portion extending across the in-

terior of the casing and resilient terminal portions angularly bent and projecting slidably through the casing at diametrically opposite points, and valve-leaves pivoted to the first mentioned portion of the valve support and arranged to rest at their edges upon the seat. 70

2. In a non-refillable bottle, a valve casing, a valve-seat within the casing, a valve support arranged within the casing and including a portion extending across the interior of the casing substantially in a plane with the valve seat, and valve-leaves pivoted to the said portion of the support and arranged to rest at their edges upon the seat. 75

3. In a non-refillable bottle, the neck of which is formed at diametrically opposite points with sockets, a valve casing fitted within the said neck, a guard carried by the casing at the upper end thereof, a valve support formed from a single length of wire bent to form an intermediate supporting portion extending diametrically across the casing and having its end portion bent to extend downwardly and inwardly and thence laterally, the laterally extending terminals of the said support being fitted through openings located at diametrically opposite points in the wall of the valve casing and projecting into the said sockets 95 whereby to hold the casing against displacement in the said neck and against removal therefrom, a valve seat extending around the inner side of the wall of the valve casing, and valve leaves hinged to the said intermediate supporting portion of the valve support and arranged to rest at their outer edges upon the said seat, the said leaves lying at opposite sides of the said portion of the support. 100

4. In a non-refillable bottle, a valve casing, a valve-seat within the casing, a valve support formed from a single length of wire bent to form an intermediate supporting portion extending diametrically across the 110 casing and to form resilient terminal portions extending downwardly and inwardly and thence laterally, the laterally extending portions of the said member being slidably fitted through the wall of the valve casing 115 at diametrically opposite points, and a valve-leaf hinged to the intermediate supporting portion of the member, and arranged to rest at its edge upon the seat. 120

5. In a non-refillable bottle, a valve casing comprising a hollow body, a ring arranged within the said body and extending circumferentially interiorly thereof and constituting a valve seat, a valve supporting member comprising a length of wire bent to 125 form an intermediate portion extending diametrically of the ring and having its end portions bend downwardly and inwardly and thence laterally to project slidably through the said body at diametrically op- 130

posite points and thereby form locking members designed to engage in seats in the neck of the bottle, and valve leaves hinged to the said intermediate portion of the supporting member and arranged to lie normally upon the said ring at their arcuate edges, the said leaves being substantially semicircular and lying one at each edge of

the said intermediate portion of the supporting member.

In testimony whereof I affix my signature 10 in presence of two witnesses.
